DEFLECTOR FOR LOCOMOTIVE EXHAUST NOZZLES

Henry J. Grill, Philadelphia, and George A. Kimber, Norristown, Pa., and Philip Stohlberger, Audubon, N. J.

Application March 13, 1937, Serial No. 130,652

2 Claims. (Cl. 230—100)

This invention relates to a steam deflector that is designed primarily for use on the exhaust nozzle of a locomotive.

At the present time there is available to the public deflectors of this general type, but with deflectors of now known designs considerable difficulty and inconvenience is being experienced by those utilizing these deflectors in that a back pressure to an undesirable high degree is set up 5 in the steam, and the deflector does not properly function to diffuse the steam over the entire cross sectional area of the stack extension and smoke stack.

With the inefficient results afforded by the 15 now-known deflectors of this type in mind, this invention has in view as its foremost objective the provision of a steam deflector for the exhaust nozzle of a locomotive, which will be effective to thoroughly diffuse the steam throughout the entire stack extension and smoke stack, 20 at the same time reducing back pressure in the steam.

In attaining this end the invention proposes the use of a ring which is intended to constitute 25 the nozzle tip, and which is carried by the nozzle, and which ring carries a plurality of deflecting elements in the form of triangular or tooth shaped members which project into the nozzle opening. When a nozzle is provided with such a tip having 30 an appropriate number of deflecting elements, say for instance four, its use is attended by the following advantages:

The exhaust steam coming from the nozzle completely fills the smoke stack, and as a result 35 the vacuum in the smoke box is greatly improved, thereby insuring a complete and more efficient combustion of fuel. Due to the fact that back pressure on the steam is decreased, the consumption of water in the running of the locomotive is correspondingly lessened, and this decrease in back pressure of the steam also affords 40 the advantage of having less wear on the rod bushings. Also due to the more perfect combustion of the fuel afforded by the proper diffusing 45 of the steam, it is possible to obtain a higher degree of super heat from the fuel.

A further advantage of the present invention is that its cost of installation is comparatively cheap, and readily carried out on the steam exhaust nozzles of locomotives without undue trouble.

Various other more detailed objects and advantages will in part become apparent, and in part be hereinafter stated, as the description of 55 the invention proceeds.

The invention, therefore, comprises a steam deflector for the exhaust nozzle of locomotives consisting of a ring carrying a plurality of deflecting elements in the form of triangularly shaped members projecting into the nozzle opening, with the points of the triangles nearest to the center of the opening.

For a full and more complete understanding of the invention, reference may be had to the following description and accompanying drawing, 10 wherein

Figure 1 is a view in plan elevation of a ring carrying the deflecting elements, in accordance with the precepts of this invention.

Figure 2 is a side view, partly in section, and partly in elevation, showing the manner in which the ring and deflector elements of Figure 1 are mounted on a steam exhaust nozzle, and

Figure 3 is a detailed view in perspective of one of the deflecting elements.

Referring now to the drawing, wherein like reference characters denote corresponding parts, a portion of a steam exhaust nozzle is shown in Figure 2, and represented by the reference character 10. The exhaust nozzle 10 has a nozzle opening designated 11. A ring, which is identified at 12, is carried by the nozzle 10, and may be affixed thereto in any preferred manner, such as by the headed bolts shown at 13.

A deflecting element is shown at Figure 3, and identified by the reference character 14. This deflecting element is of a triangular formation, as illustrated, having converging sides 15 which terminate in a point 16.

The ring 12 carries a desired number of deflecting elements 14. In the illustrated embodiment of the invention, the ring 12 is shown as carrying four of these deflecting elements, although obviously this number may be varied, as occasion demands. The deflecting elements 14 may be attached to the ring 12 in any approved manner, and in the form of the invention shown in the drawing, each of the deflecting elements is shown as having an extension 17 provided with openings 18 through which pass screw fastening elements designated 19.

Steam coming from the opening 11 of the nozzle 10 will strike against the deflecting elements 14, and be diffused in a highly efficient manner, as above pointed out. Due to the fact that the cross sectional area of the opening 11 is only slightly reduced by the deflecting elements 14, the back pressure created by these deflecting elements is comparatively small. At the same 55

time proper diffusing action in the steam is obtained.

While a preferred specific embodiment of the invention is hereinbefore set forth, it is to be clearly understood that I am not to be limited to the exact construction illustrated and described, because various modifications of these details may be provided in putting the invention into practice within the purview of the appended claims.

10 We claim:

1. A steam deflector for the exhaust nozzles of locomotives comprising a ring member, a plurality of flat pointed tooth shaped deflecting elements carried by the ring member, a flat face of each deflecting element being fastened to a flat face of the ring member, each tooth shaped deflecting member having its point extending into the opening of the ring member, and means for affixing each of the tooth shaped deflecting elements to the ring member.

2. A steam deflector for the exhaust nozzles of locomotives comprising a ring member having a flat surface, a plurality of flat pointed tooth shaped deflecting elements carried by the ring member with a flat face of each deflecting element being fastened to the flat face of the ring member, each tooth shaped deflecting element projecting inwardly from the said ring member with the portion of the deflecting element which extends beyond the ring member being substantially triangular in formation with the apex of the triangle disposed nearest to the center of the ring member and the base of the triangle being defined by the inner edge of the ring member, and means for affixing each of the tooth shaped deflecting elements to the ring member.
